CARRYING TRAY FOR EQUIPMENT FOR MAKING BLOOD TESTS

Mamie Roberts, North Little Rock, Ark.

Application August 7, 1952, Serial No. 20,939

Term of patent 14 years

(Cl. D58—26)

To all whom it may concern:

Be it known that I, Mamie Roberts, a citizen of the United States, residing at 1003 Park Drive, North Little Rock, Arkansas, have invented a new, original, and ornamental Design for a Carrying Tray for Equipment for Making Blood Tests, of which the following is a specification, reference being had to the accompanying drawing, forming a part hereof.

Fig. 1 is a perspective view of a carrying tray for equipment for making blood tests, showing my new design.

Fig. 2 is a horizontal sectional view taken on the line 2—2 in Fig. 1.

I claim:

The ornamental design for a carrying tray for equipment for making blood tests, as shown.

MAMIE ROBERTS.
